Franklin Limmons, of Washington, D.C.

Assignor to

William Miller, of Providence, R.I.

Letters Patent No. 2146-Dated July 18-1865.

Design for a Medallion of Mr. W. G. Ward.

The schedule referred to in this Letter Patent is making part of the same.

To all whom it may concern;

Be it known, that I, Franklin Limmons, of Wash-
City of Washington, D.C. have originated and produced a new model, of which the accompanying photograph is a true representation.

What I claim as my invention or production, and desire to secure by Letters Patent is The mezzo-relievo or medallion portrait of Secretary Ward represented by the photograph herewith attached.
